UNITED STATES PATENT OFFICE.

HARRY FULENWIDER AND JESSE FULENWIDER, OF SAVANNAH, GEORGIA.

ASPHALT-SHINGLE FASTENER.

Application filed May 27, 1925. Serial No. 33,208.

This invention relates to shingle fasteners for securing shingles to a roof, and which are especially designed to hold down the free ends of flexible shingles when laid diagonally.

One of the objections to the use of flexible shingles as heretofore laid, has arisen from the tendency of the shingles to curl up at the free ends, thus permitting rain to blow beneath the shingles and causing leakage through the roof. Fasteners have been invented, and to some extent used, for securing the free ends of the shingles to the roof, but in so far as we are aware they have had a binding effect upon the shingle, inhibiting its freedom of thermal expansion or contraction thereby causing a warping of the shingle, making an unsightly roof and permitting water to enter beneath the shingles.

The present invention has for its principal object the provision of means for holding down the free end of the shingle while at the same time permitting freedom of motion of said free end so that the shingle may remain flat while accommodating itself to thermal expansion or contraction.

Another object of the invention is to provide a shingle fastener adapted to cooperate with a shingle having a pre-folded free end, the construction of said fastener permitting the positioning of the shingle and the securing of the same in place without the necessity of bending the shingle "on the job" along the line upon which the end is folded, as has been necessary in certain previously known shingle fasteners and results in the later development of a crack or break in the shingle along the line of fold.

A further object of the invention is the provision of a shingle and shingle fastener so arranged as to form a ventilating crevice between the edges of the shingle and the edges of the adjacent shingles of the underlying course when the shingle is in place relative to the fastener.

Another object of the invention is to construct a shingle fastener of the type indicated which is entirely concealed when the shingles are in place and which provides spacing means which renders the fastener self-allocatable, and also serves as a spacer between the edges of the folded end of the shingle and the edges of the adjacent shingles in the previously laid course, thus ensuring ventilation and perfect drainage, avoiding dampness of the roof and thereby

increasing the length of life of the shingles.

Other objects of the invention will appear as the description of the following illustrative embodiments thereof proceeds.

60

In the drawings:—

Figure 1 is a face view of a portion of a roof shingled with flexible shingles and employing our invention.

Figure 2 is a section taken along the line 65 2—2 of Figure 1.

Figure 3 is a view similar to Figure 2 but showing the shingle in separated relation with respect to its fastening means.

Figure 4 is a perspective view showing 70 one of the pre-folded shingles.

Figure 5 is a perspective view of one embodiment of my improved shingle fastener.

Figures 6 and 7 are respectively plan and beneath views of a slightly modified form of 75 the invention.

Referring now in detail to the several figures, the reference numeral 1 represents adjacent shingles of an underlying course having their adjacent corners 2, 2 in abutment, forming an inverted V-shaped valley 3. The shingle fastener 4, which is illustrated in Figure 5, is placed over the abutting corners of said shingles and secured thereto in any suitable manner as by nails passing through the apertures 5. In Figure 5 the apertures are shown as being pre-formed but in practice it may be advantageous to drive the nails or other securing means directly through the material of the fastener. The fastener 4 is preferably made of sheet metal having on its under side a V-shaped depression 6 formed by pressing up the material of the fastener in a manner which will be clearly understood from an inspection of Figure 5. The V-shaped depression has preferably the same angularity as that of the V-shaped valley 3, and in positioning the fastener prior to securing the same in place, the V-shaped depression should be placed in coincidence with the V-shaped valley so as to form a pocket 9 for a corner 7 of the shingle 8. The depth of the pocket 9 is equal to the thickness of the adjacent shingles 1, plus the depth of the depression 6 so that there is ample room to permit the folded corner 7 of the shingle 8 to slide into said pocket without binding and to be freely retained therein so as to permit unrestricted movement of the shingle in an up and down direction when expanding or contracting. The altitude of the folded corner of the shingle is preferably

less than that of the pocket so that ventilating grooves or crevices are formed between edges of the shingle forming said corner and the sides of the pocket, and of the adjacent shingles in the lower course. The corners of the fastener are, by preference, cut away diagonally to prevent them projecting beyond the superposed shingle. The shingle 8 is preferably folded at the factory 10 while subjected to a proper degree of heat to permit the bending thereof without breaking or cracking or the flaking off of the slate particles with which the flexible shingles are frequently coated. The freedom of movement of the folded corner 7 within the pocket 9 avoids the necessity of forcing the shingle in place or straightening it out or in any other way abusing the pre-formed fold so that the shingle, when laid, is in as 20 perfect condition as when first manufactured. This cannot be said of shingles of which it is necessary to force a corner beneath the fastening means while the shingle is in straight condition, the shingle being 25 then folded over the fastening means.

In Figures 6 and 7 I have shown a form of the invention which is similar in its broad features to that shown in Figure 5, but distinguished therefrom by having slits 30 made in the material adjacent the apex and ends of the V-shaped depression, the material being bent downwardly at the ends of such depression to form lugs 10 and 11. Said lugs form spacers for the fastener, the lugs 10 engaging with the upper edges of 35 the adjacent shingles 1 above the abutting corners thereof, and the lugs 11 engaging the edges of said adjacent shingles which form the sides of the V-shaped valley 3. 40 When the undeturned corner 7 of a pre-folded shingle is inserted into the pocket 9, the edges of said undeturned corner engage with the lugs 11, preventing said edges from coming into close abutment with the 45 edges of the adjacent shingles. A trough 12 is thus formed which affords a ventilating space between said edges, preventing the retension of dampness and preserving the life of the shingles.

50 While we have herein disclosed what we believe to be a practical embodiment of our invention it is to be understood that it may be exemplified in numerous other alternative

constructions without transcending the scope of the appended claims.

Having described our invention what we claim as new and desire to secure by Letters Patent, is:—

1. A shingle fastener comprising a plate adapted to overlie the juxtaposed corners of adjacent diagonally laid shingles in a course and having a depression in its lower face adapted to coincide with the valley between the lower adjacent edges of said shingles to form a pocket of greater depth than the thickness of a shingle. 60

2. A shingle fastener comprising a plate adapted to overlie the juxtaposed corners of adjacent diagonally laid shingles in a course and having a depression in its lower face 70 adapted to coincide with the valley between the lower adjacent edges of said shingles to form a pocket of greater depth than the thickness of a shingle, the sides of said pocket terminating in edges which intersect 75 the side and bottom edges of said fastener, said fastener being adapted to be secured to said adjacent shingles.

3. In combination, a shingle fastener comprising a plate adapted to overlie the juxtaposed corners of adjacent diagonally laid shingles in a course, and having a depression in its lower face adapted to coincide with the valley between the lower adjacent edges of said shingles, to form a pocket of greater 80 depth than the thickness of a shingle, and a shingle having an undeturned corner adapted to be inserted in said pocket, the altitude of the undeturned end being less than that of the pocket. 85

4. A shingle fastener comprising a plate having a depression in its lower face adapted to coincide with the valley between the lower adjacent edges of a lower row of shingles over which it is adapted to be fastened and to form with said valley a pocket of greater depth than the thickness of a shingle to receive the bent corner of an overlying shingle and said depression being formed with lugs for spacing said bent corner from the sides of said pocket, thereby providing ventilating spaces. 100

In testimony whereof we have hereunto set our hands.

HARRY FULENWIDER.
JESSE FULENWIDER.
